INVENTOR:

John Jaros.

BY

Frank P. Shepard.

ATTORNEY.

UNITED STATES PATENT OFFICE.

JOHN JAROS, OF OKLAHOMA, OKLAHOMA.

WRENCH.

1,368,801.

Specification of Letters Patent. Patented Feb. 15, 1921.

Application filed November 3, 1919. Serial No. 335,254.

To all whom it may concern:

Be it known that I, JOHN JAROS, a subject of the Emperor of Austria, and a resident of Oklahoma city, in the county of Oklahoma and State of Oklahoma, have invented certain Improvements in Wrenches, of which the following is a specification, reference being had to the accompanying drawings.

10 The invention pertains to wrenches in which the jaws are relatively movable.

In wrenches of this class one of the jaws is unusually formed integrally on the end of a shank and the other jaw is fitted slidably on the shank, a screw being provided to force the jaws together.

One object of the invention is to provide means whereby the sliding jaw will fit or embrace the shank more closely while being 20 acted upon by the screw.

Other objects and advantages of the invention will be set forth in the ensuing description.

Figure 1 of the drawings is an elevation 25 view of the improved wrench, with portions broken away to expose interior construction.

Fig. 2 is a sectional view taken on the line 2-2 of Fig. 1.

Fig. 3 is a view in the same direction as 30 Fig. 1, showing the sliding jaw.

Fig. 4 is a similar view showing a fragment of the shank.

Fig. 5 is an enlarged sectional view taken on the line 5-5 of Fig. 1, with the shank 35 and a certain spring omitted.

Like characters of reference designate like parts in all the figures.

The wrench shown includes the shank 6 with the stationary jaw 7 formed integrally 40 on its upper end; the movable jaw 8 which is fitted to slide on the shank and co-act with the jaw 7; and a tubular handle 9 which is screwthreaded to the lower end of the shank and adapted to force the jaws together.

45 For purposes later shown, the movable jaw 8 is in skeleton form, and in this instance the upper end 9^b of the handle 9 is journaled through the lower annular portion 8^b of said jaw and has a shoulder 9^c 50 which bears against said annular portion.

A nut 10 is screwthreaded to the handle 9 above the annular portion 8^b of the jaw 8 to hold the parts in assemblage; and a spring washer 11, shown shaded in solid black in 55 Fig. 1, is interposed between said nut and

annular portion to frictionally hold the handle from revolving too easily.

For convenience in handling the wrench, a compression spring 12 is interposed between the removable lower end 13 of the handle 9 60 and the shoulder 6^b of the shank 6, this spring being held in line by a downward extension 6^c of said shank and by a sleeve 13^b on the lower end portion 13 in which said extension slidably fits.

65 To afford quick-action adjustment of the movable jaw 8, only a small portion 6^d covering, say, sixty degrees of the circumference of the shank 6 is threaded, and a like or slightly greater portion of the threads in 70 the handle 9 are cut away as at 9^d in Fig. 5.

By this arrangement the handle 9, when revolved to a certain position, is freed from threaded engagement with the shank 6 and 75 may be freely slid thereon for quick movement of the jaw 8.

The lower annular portion 8^b of the skeleton jaw 8 is integrally joined to the upper portion 8^c by the two connections 8^d which, for a portion of their length downward from 80 said upper portion 8^c, have a sliding fit against the edges of the shank 6.

The S-curve formation of the connections 8^d allows them to be put under spring tension by screwing the handle 9 up against 85 the annular portion 8^b of the jaw 8, said connections assuming the position indicated to an exaggerated degree by the dotted lines in Fig. 3.

In being placed under tension, each connection 8^d "pivots" at or near its upper and lower ends, so that the central portions of 90 said connections which lie inside of the straight lines A-A (Fig. 3) passing through the "pivotal" points 8^e are forcibly 95 buckled inward against the shank 6 and take up lost motion between said shank and the jaw 8.

The following is claimed:

1. In a wrench, a shank having a jaw at 100 one of its ends, a second jaw slidable on the shank, means on the shank for forcing the jaws together, the slidable jaw being provided with yielding elastic arms so formed that when acted upon by the forcing means 105 they tighten their embrace on the shank.

2. In a wrench, a shank having a jaw at 110 one of its ends, a second jaw slidable on the shank, means on the shank for forcing the jaws together, the sliding jaw being skele-

ton in form with outward yielding elastic connections with curved portions and so shaped that when acted upon by the forcing means they buckle inward and bind the shank.

3. In a wrench, a shank having a jaw at one of its ends, a second jaw slidably embracing the shank, means on the shank for forcing the jaws together, that portion of the sliding jaw against which the forcing means acts being connected to the remainder of said jaw

by yielding elastic curved connections which are adapted to be sprung from a straight line by action of the forcing means and the portions between the curved parts and the sliding jaw buckled inward to thereby bind the shank, the shank having a toothed portion and a handle having threads to engage therewith.

Witness my hand this 15th day of October, 20
1919.

JOHN JAROS.
